UNITED STATES PATENT OFFICE.

STANLEY S. MILLER, OF GLENS FALLS, NEW YORK.

PAPER-MAKING MACHINE.

Application filed July 27, 1921. Serial No. 437,965.

To all whom it may concern:

Be it known that I, STANLEY S. MILLER, a citizen of the United States, residing at Glens Falls, in the county of Warren and State of New York, have invented certain new and useful Improvements in Paper-Making Machines, of which the following is a specification.

My invention relates to Fourdrinier paper making machines. It has of late been the practice in using machines of this type to run the wire aprons upon which the web of paper is formed at increasingly high speeds, it now being not uncommon for the apron to attain a speed from six hundred to a thousand feet per minute. When these machines are run at such high speeds much difficulty and inconvenience has been experienced where the deckle straps leave the surface of the wire apron and pass around the supporting pulleys, by reason of the fact that the centrifugal force developed by the deckle bands as they make the turn about said pulleys causes more or less water and wet paper stock which adheres to the deckle straps to be thrown off and toward the rear of the machine, to the inconvenience of workmen and often to the serious injury of the web of paper being formed, necessitating the section of the web thus spattered with the water and paper stock being removed and discarded, with incident loss in production and delays in the operation of the machine.

My invention has for its object to arrest, collect and take care of the material thus thrown off from the deckle straps by centrifugal force.

In the accompanying drawings,

Figure 1 is a side view of a portion of a paper-making machine embodying my invention; and

Figure 2 is a top plan view of a portion of such machine.

In the drawings, 2 designates the framework of the machine; 3 the endless wire apron upon which the web of paper is formed, and 5 the rollers that support the apron in the usual manner. I do not show means for imparting motion to the wire apron nor for feeding the paper stock thereto, or taking away the web of paper after it has been formed, as these may be of any usual or preferred construction and arrangement, and they form no part of my present invention.

4 designates a deckle strap, of usual or preferred construction, the machine being provided with two of these. 6 is the pulley about which the deckle strap makes its turn 60 toward the delivery end of the machine. This pulley is supported upon a shaft 7.

A bracket 8, supported by some part of the framework 2 in proximity to, and preferably a little to the rear of, the pulley 6, carries an inwardly extending arm to which is secured a guard and collector 10 located directly to the rear of the deckle strap and with its lower end near to the upper surface of the wire apron 3. The guard and collector is wider than the deckle strap and is in shape a sort of curved trough-like receptacle set upright, having an inner side wall 11 and a wall 12 at right angles thereto, curved to constitute the bottom of the 75 lower part of the collector guard and the rear wall of the upper part thereof. The lower portion of the guard and collector 10 curves forwardly toward the deckle strap, its lower forward end being approximately 80 parallel with the upper surface of the wire apron and about three-quarters of an inch above the surface thereof. The guard and collector is thus open toward the deckle strap and on one, the outer, side. Into it 85 is discharged, and by it collected, the material thrown by centrifugal force from the deckle strap, as has been described. In the converging space between the lower end of the guard 10, the upper surface of the wire 90 apron, and the surface of the deckle strap as it is directed by the pulley away from the wire apron, I arrange a small roller 13, mounted upon a shaft 14 supported in bearings carried by the guard 10. The shaft 95 14 is driven, by belt 15, from the shaft 7, its direction of rotation being indicated by the arrow. The roller 13 is preferably wider than the deckle strap but not so wide as the forward open lower end of the guard 10, in 100 practice being about two inches in diameter and four inches long. It is preferably located so that its periphery is about a quarter of an inch, at the nearest point, from the surface of the deckle strap and a like 105 distance from the upper surface of the wire apron 3. It is rotated so that its peripheral speed is much less than that of the deckle strap, 100 feet per minute being about the right speed for it. Its function is to arrest material thrown off from the lower portion 110 of the deckle strap and collect the same.

upon its peripheral surface from which it is removed by a scraper 17 and delivered into the lower pan-like portion of the guard or collector 10. Such material as is not arrested by the roller 13 is gathered by the doctor 16 and delivered into the collector or guard. The rear, bottom, wall 12 of the guard is extended sufficiently far to one side to deliver the material collected beyond the edge of the web of paper that has been formed upon the wire apron so that it will not come in contact with or injure the web. The material thrown off by the deckle strap may be sufficiently fluid in character to flow from the guard, otherwise it is washed off by a flowing stream of water supplied for that purpose.

The device described has proven to be successful for the purpose for which it is intended, and effects a large saving in the product of the machine and enables the machine to be run practically continuously. It may be quickly and easily applied to a machine already installed, and is inexpensive.

What I claim is:—

1. In a high speed Fourdrinier paper-making machine, the combination with the wire apron and deckle straps thereof, of means for arresting and collecting the paper stock and water thrown by centrifugal force from the deckle straps where they leave the surface of the apron on which the web of paper is formed, means for conducting the paper stock and water so collected away from the paper being produced.

2. In combination with the wire apron and deckle straps of a high speed Fourdrinier paper-making machine, a collector located close to and in rear of each deckle strap arranged to receive and collect the material thrown off from the deckle strap as it leaves the surface of the apron and a conductor for leading away the material so collected so it will not be deposited on the paper being formed.

3. The combination stated in claim 2 when the collector is in the form of a trough open toward the deckle strap as it leaves the surface of the apron, the trough

having a side wall and a rear and bottom wall.

4. The combination stated in claim 3 having the bottom wall of the collecting trough extended laterally outwardly to deliver the material collected beyond the edge of the web of paper being formed.

5. The combination with the wire apron and the deckle straps of a Fourdrinier paper-making machine, of a guard and collector located in rear of each deckle strap to receive and collect the material thrown by centrifugal force from such strap as it leaves the surface of the apron, and a small roller located between the lower portion of the said guard and collector, the apron and the deckle strap, and means for turning the roller at a speed less than that of the deckle strap, the roller serving to intercept some of the material thrown off from the deckle strap and deliver it to the guard and collector.

6. The combination stated in claim 5 including a scraper for removing the material adhering to the surface of the roller and delivering it to the collector guard.

7. In combination with the wire apron and deckle straps of a Fourdrinier paper-making machine, a collector located close to and in rear of each deckle strap, the collector being in the form of a trough open toward the deckle strap as it leaves the surface of the apron, and a doctor bearing upon the deckle strap above the lower portion of the collector arranged to remove and intercept material carried upwardly by the deckle strap and deliver such removed material to the collector.

8. In combination with the wire apron and deckle straps of a Fourdrinier paper-making machine, a collector for receiving the material thrown off from the deckle strap as it leaves the surface of the apron and delivering it away from the paper being produced, and adjustable supporting means for the collector uniting it with the frame of the machine and permitting it to be adjusted with reference to the deckle strap and the edge of the apron.

STANLEY S. MILLER.
